United States Patent Office.

EARL A. WHITE, OF ROCK ISLAND, ILLINOIS, ASSIGNOR TO HIMSELF AND
BASIL D. BUFORD & CO., OF SAME PLACE.

Letters Patent No. 96,066, dated October 19, 1869.

IMPROVED DEVICE FOR GRINDING METAL PLATES.

The Schedule referred to in these Letters Patent and making part of the same.

To all whom it may concern:

Be it known that I, EARL A. WHITE, of Rock Island, in the county of Rock Island, and State of Illinois, have invented certain new and useful Improvements in Apparatus for Grinding Metal Plates; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to the grinding or polishing of metals, more especially intended for grinding steel plows and cultivators; and

The invention consists in the construction of certain novel devices for holding and moving the plate that is being ground, as hereinafter more fully explained.

Figure 1 is a side elevation, shown partly in section, on the line *y y* of fig. 2;

Figure 2 is a vertical section, on the line *x x* of fig. 1; and

Figures 3, 4, and 5, are views of portions shown in detail.

In the manufacture of the steel plows and cultivators used in the western States, it is necessary to smooth or polish the surface of the metallic plates of the same, which is generally done by grinding them on a grindstone. This is usually effected by the operator holding the article to be ground in his hand, or sometimes by resting it on a swinging support, and pressing it against the stone—in either case a tedious, laborious, and unpleasant operation.

The object of my present invention is to provide a means whereby the operation of grinding may be more speedily and easily effected.

To accomplish this object, I secure the plate to be ground to the end of a lever, in such a manner that its surface can be brought into contact with the stone, and at the same time can be moved and controlled at will by the operator.

In the drawing—

A represents a grindstone, mounted on a frame, *B*.

In front of the stone *I* locate a support or fulcrum for the lever, which, in this case, consists of a strong rod, *F*, having a screw-thread on it, and screwing into a nut, *a*, secured to a cross-bar, *L*, secured to the frame *B*, the upper portion of the rod *F* being supported by a frame, *I*, as shown in figs. 1 and 2.

I then provide a block, *D*, with its upper surface of a form corresponding to the shape or form of the article to be ground, and provide it with the means of securing the plate firmly thereto.

In fig. 4 is represented a block, adapted to holding

a cultivator-share, *H*, which is secured to the block *D* by means of a loop, *t*, which is secured to the back of the plate, and fits into a recess in the block, to which it is secured by a key, *e*, as shown both in figs. 1 and 4.

Figure 5 represents another holding-block, specially adapted to grinding the rotary or wheel-coulter used with plows.

In this case, a pin, *V*, projects from the upper face of the block *T*, near one side, and a wheel, *n*, is inserted in a recess near the opposite side, in such a manner that its periphery shall project slightly above the surface of the block *T*, and thus form a bearing for the coulter *G* to rest upon, when the latter is mounted on the pin *V*, as represented.

These blocks, whatever may be their form or number, are pivoted to the end of a lever, *C*, by a pin, *n'*, as represented in fig. 1, the pin being removable, so that the blocks may be changed as occasion requires, the same lever *C* answering for all or for any number of blocks.

The lever *C* is simply a strong stick of timber, having its front end mortised to receive the tongue *m* of the holding-blocks, and having a series of cavities, *o*, formed in its under surface to fit on the rounded head of the support *a*, as represented in fig. 1, these parts thus forming a ball and socket, or universal joint, which permits the lever to be moved or turned in any direction.

The rear end of the lever *C* is rounded on its upper surface, and is made wider, for the purpose of forming a seat, astride of which the operator sits, for the double purpose of holding it steady, and applying his weight, more or less, to press the article against the stone.

There is also a curved rod, *J*, attached to the lever *C*, near its rear end, as represented in figs. 1 and 3, to form a handle, to be grasped by the left hand, to assist in turning and guiding the lever, and the plate attached to it, as may be necessary.

In each of the blocks *D* and *T* there is a hole, for the insertion of a lever, *E*, to be grasped by the right hand of the operator, so as to tip the block back and forth on the pivot *a*, and thus move the plate, as may be desired, to bring all parts of its surface in contact with the stone.

By these means, the process of grinding and polishing the surface of the plates is greatly facilitated, and the operator is kept at such a distance from the stone that he is incommoded by the grit and dust to a much less extent than is usual where he has to hold the article in his hands, and has to stand close up to the stone.

By raising or lowering the support *F*, the lever can be adjusted to any desired height; and by swinging the lever *C* laterally, and turning it on the head of

the support F, a plate of any size or form can be brought in contact with the stone over its whole surface; while, by the lever J, it can be tipped in the opposite direction, so as to bring all parts of its surface, or either edge, more or less in contact with the stone.

By this provision for a universal movement of the parts, any size and form of a plate can be ground with facility; and, by the application of weight upon the lever C, the article can be pressed against the stone with any desired degree of force, and thus the process of grinding be greatly expedited.

By using the block T, with the friction-roller n, the rotary coulter, or disk G, when applied to the stone, is caused to revolve slowly, and thus brings all parts of its surface successively against the stone. After one side has been ground it is reversed, and the other side is ground in like manner.

Thus, by my invention, the process of grinding, which has heretofore been a slow, tedious, and laborious, as well as disagreeable and unhealthy one, is rendered comparatively easy, rapid, and pleasant.

Having thus described my invention, What I claim, is—

1. The lever C, mounted on a fulcrum, in the manner described, so that it may be turned or adjusted at any desirable angle, laterally or vertically, and arranged to be operated by the attendant, substantially as set forth.
2. In combination with the lever C, the hinged holding-block, substantially as described.
3. The hand-lever E, in combination with the holding-blocks D T, as set forth.
4. The holding-block T, provided with the pin v and roller n, substantially as set forth.
5. The adjustable fulcrum F, having a ball or spherical head mounted in the rest L, and arranged to operate as herein described.

EARL A. WHITE.
